UNITED STATES PATENT OFFICE.

WILBUR F. BUDLONG, OF SAN JOSE, CALIFORNIA, ASSIGNOR TO BEAN SPRAY PUMP CO., OF SAN JOSE, CALIFORNIA.

VALVE.

1,001,246.

Specification of Letters Patent. Patented Aug. 22, 1911.

Application filed March 14, 1908. Serial No. 421,138.

To all whom it may concern:

Be it known that I, WILBUR F. BUDLONG, a citizen of the United States, residing at San Jose, in the county of Santa Clara and 5 State of California, have invented certain new and useful Improvements in Valves, and do hereby declare that the following is a full, clear, and exact description of the same, reference being had to the annexed 10 drawings, making a part of this specification, and to the letters and figures of reference marked thereon.

The object of my invention is to provide a construction of valve which will require 15 no internal screws, screw threads, bolts or pins, whereby the number of parts will be reduced, and especially those parts eliminated that are small and expensive and liable to corrode, and liability to rusting or 20 sticking in any of its parts avoided, and the parts capable of being easily and quickly assembled or taken apart for cleaning.

In the drawings, Figure 1 is a vertical section of a valve embodying my invention; 25 Fig. 2 a top plan view thereof; and Fig. 3 a detail view in vertical section of the valve cover.

In the form of my invention illustrated in the drawings, a valve chamber A is employed, which may be cast or machined, and 30 which concentric with the inlet port α in its lower end has an annular recess for the reception of a valve seat B of such material and form as is suited to the kind of valve 35 used, my invention not being limited to any particular type of valve. An outlet α' is shown in the side of the valve chamber. As a ball valve C is the one illustrated, the valve seat is of ring or annular form. The 40 top of the valve chamber A is closed by a cover, which may be cast or machined, consisting of a head or cap D, and a cage-like body portion E in the form of a cylindrical shell having its walls provided with holes 45 or openings for the passage of liquid, and whose internal form and size are such as to constitute guiding means for the valve in moving to and from its seat when the valve is, for example, of the ball type illustrated.

The lower end of the cover body engages the 50 top of the valve seat to hold it in place, and preferably the distance between the lower end of said body and the under side cap or head is the same as the distance from the upper edge of the valve chamber A to the 55 bottom of such chamber on the inside. In order to secure the proper holding effect of the cover upon the valve seat, the valve seat is a little thicker than the depth of the annular recess in which it is placed. The 60 valve cover and the valve chamber may be secured together in any desired way, as, for example, by means of a screw thread connection or engagement between the cover just below its cap or head, and the inner 65 wall of the valve chamber thereat, or by screws or bolts, or, as is shown in the drawings, by means of an inverted U-formed yoke F, whose two vertical legs have lugs that hook beneath the bottom of the valve chamber on the outside thereof, and whose horizontal member extends diametrically across the top of the valve structure, and has a threaded opening for the reception of a set screw or bolt G, which impinges upon the 75 top of the valve cover, and thereby serves to clamp the parts tightly together. If preferred, when the yoke is used, some other clamping device may be used in place of the set screw or bolt. 80

If the contacting surfaces of the valve seat and the recess provided in the valve chamber for the valve seat, are sufficiently true to make a liquid-tight joint, no gasket or other packing need be used, but as a 85 matter of precaution, it is advisable to use a gasket H between the under side of the valve seat and the bottom of its recess, and when such a gasket is used, another gasket I of like thickness should be placed between 90 the cap or head of the valve cover and the top of the valve chamber. To assemble the parts of the valve illustrated in the drawings, the valve seat and gasket are placed in the annular recess in the bottom of the 95 valve chamber, next the valve C is put in place, and then the cover, and the parts secured together by the clamp.

Having thus described my invention, what I claim is—

An automatically operating valve having a valve chamber, a valve seat having threadless connection with the chamber and separable therefrom, a removable cover for the valve chamber, means interposed between cover and seat, whereby the cover holds the seat in position, the internal surfaces of the

cover and chamber being threadless, and means external to the cover and chamber to secure the cover in position.

In testimony whereof I affix my signature in presence of two witnesses.

WILBUR F. BUDLONG.
